Application March 14, 1955, Serial No. 35,025

Term of patent 14 years

(Cl. D44—9)

Fig. 1.

Fig. 2.

Fig. 1 is a perspective view of a cup or similar article showing my new design.

Fig. 2 is a panoramic view of the outer surface of the design.

The internal ornamentation shown in Fig. 1 is the same on the portion of the inside of the cup that is not shown as on the portion shown. The motif shown on the outside of Fig. 1 is shown in the right portion of Fig. 2, and the left portion of Fig. 2 occupies the outside portion not shown in Fig. 1.

The dominant features of the design reside in the portions shown in full lines.

I claim:

The ornamental design for a cup or similar article, substantially as shown and described.
